(57) **CLAIM**

The ornamental design for a beverage container lid, substantially as shown and described.

DESCRIPTION

FIG. 1 is a rear side top perspective view of a beverage container lid;

FIG. 2 is a top plan view thereof, shown with the slider closed;

FIG. 3 is a top plan view thereof, shown with the slider open;

FIG. 4 is a rear elevational view thereof;

FIG. 5 is a front elevational view thereof;

FIG. 6 is a right side elevational view thereof;

FIG. 7 is a left side elevational view thereof;

FIG. 8 is a bottom elevational view thereof; and,

FIG. 9 is a rear bottom perspective view thereof.

The broken lines in the drawings illustrate portions of the beverage container lid that form no part of the claimed design.

1 Claim, 5 Drawing Sheets
